UNITED STATES PATENT OFFICE.

CHARLES EDWARD HAVILAND, OF LIMOGES, FRANCE.

DESIGN FOR A SANDWICH-PLATE.

SPECIFICATION forming part of Design No. 21,685, dated July 5, 1892.

Application filed June 7, 1892. Serial No. 435,896. Term of patent 14 years.

To all whom it may concern:

Be it known that I, CHARLES EDWARD HAVILAND, a citizen of the United States, residing at the city of Limoges, in the Republic of France, have invented and produced a new and original Design for a Sandwich-Plate, and Cup and other Articles, of which the following is a specification, reference being had to the accompanying drawings, forming a part thereof, and in which—

Figure 1 is a top view of a plate bearing my design, the cup being indicated by dotted lines, so as not to hide a portion of said plate; Fig. 2, a side elevation of same, partly in section on the dotted line 2 2 of Fig. 1, and Fig. 3 a detached section of a portion of said plate on the dotted line 3 3 of Fig. 1.

The leading features of my design consist of the shape and ornamental configuration of

the plate, as shown. The cup presented does not form an essential feature of the design and is illustrated for purposes of completeness, the plate being usually accompanied by a cup adapted to be carried by it. The plate bears the curved scalloped ornate scrolls A 20 B, connected at one point by the edge C and at another bearing the conventionalized foliate spray D.

What I claim is—

The design for a plate or other article, substantially as shown and described. 30

Signed at the city of Limoges, in the Republic of France, this 25th day of May, 1892.

CHARLES EDWARD HAVILAND.
